Primary Examiner — Catherine A Tuttle(74) *Attorney, Agent, or Firm* — Heedong Chae; Lucem, PC(57) **CLAIM**

The ornamental design for a cosmetic container, as shown and described.

DESCRIPTION

FIG. 1 is a perspective view of the cosmetic container showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in FIG. 7 are included for the purpose of illustrating the portions of the cosmetic container that form no part of the claimed design.

1 Claim, 6 Drawing Sheets(56)
